JOHN L. DRAKE, OF TOLEDO, OHIO, ASSIGNOR TO LIBBEY-OWENS-FORD GLASS COMPANY,
OF TOLEDO, OHIO, A CORPORATION OF OHIO

METHOD AND APPARATUS FOR PRODUCING SHEET GLASS

Application filed March 7, 1930. Serial No. 433,910.

The present invention relates to a method and apparatus for producing sheet glass.

While this invention is primarily designed for use in connection with the Colburn process for producing sheet glass, as exemplified in Colburn Patent No. 1,248,809, granted December 4, 1917, it is of course not necessarily restricted to use in such connection as it can well be adapted to other types of sheet glass forming apparatus. In the Colburn process, however, the glass sheet is continuously drawn upwardly from a bath of molten glass contained in a suitable receptacle or draw-pot and after becoming substantially set, although while still in a semi-plastic condition, is deflected into a horizontal plane and passed horizontally through a combined drawing and flattening mechanism into and through an annealing leer.

An important object of the invention resides in the provision of a method and apparatus wherein the formation of surface defects or irregularities in the sheet will be reduced to a minimum so that a flatter, smoother, and more uniform thickness of sheet may be produced.

Another object of the invention is the provision of a method and apparatus for minimizing the formation of surface irregularities in the sheet during the formation thereof by subjecting said sheet to a wiping or smoothing action at substantially the base or meniscus thereof.

A further object of the invention is the provision of such a method and apparatus as described above wherein the sheet may also, if desired, and during the deflecting thereof from the vertical to the horizontal, be dragged over suitable means producing a smoothing or flattening action upon the surface thereof.

Other objects and advantages of the invention will become more apparent during the course of the following description when taken in connection with the accompanying drawings.

In the drawings wherein like numerals are employed to designate like parts throughout the same,

Fig. 1 is a vertical longitudinal section through sheet glass apparatus constructed in accordance with the present invention,

Fig. 2 is a side elevation of a portion thereof,

Fig. 3 is an elevation showing a part of the structural details, and

Fig. 4 is a sectional view of an alternative arrangement.

Referring now to the drawings, 5 designates a glass sheet continuously drawn upwardly from a mass of molten glass 6 contained in a suitable receptacle or draw-pot 7 and supplied thereto from any suitable type of furnace 8. The sheet 5 is drawn upwardly for a suitable distance and then, while still in a semi-plastic condition, is deflected about the rotatable bending roll 9 into a substantially horizontal plane as indicated at 5a, said sheet being then passed over a so-called idler 60 roll 10 and draw table 11 into and through an annealing leer (not shown).

In the Colburn process as ordinarily practiced, suitable knurled rollers or other width maintaining means are positioned to engage 75 opposite edges of the sheet at the base thereof to prevent narrowing of the sheet as it is drawn upwardly. However, in accordance with the present invention, the usual sheet edge engaging means are omitted and there 80 are substituted therefor the preferably metallic members 12 and 13 which extend the entire width of the sheet and are adapted to engage opposite surfaces thereof at the base 85 or meniscus 14. These members are in the form of hollow, substantially rectangular casings and are provided not only to maintain the sheet to width, but also to minimize the formation of surface defects or irregularities in said sheet as it is being formed. Thus, these members produce a wiping action 90 upon opposite surfaces of the glass as it is drawn upwardly therebetween and thereby have a tendency to flatten or smooth out the 95 glass so as to minimize the formation of surface irregularities in the sheet as it is being formed whereby to aid in producing a flatter, and smoother sheet of a more uniform thickness.

The members 12 and 13 are preferably supported slightly above but closely adjacent the molten bath 6, and the inner adjacent side walls 15 and 16 of said members are arcuately curved transversely as shown, with the lower portions thereof fitting substantially into the curvature of the sheet meniscus 14. The members are adapted to be internally cooled by the circulation of a suitable temperature control medium therethrough and the said members, or at least those portions contacting with the glass, are preferably constructed from a suitable non-corrosive material such as nickel, nichrome, monel, or the like, which will take and retain a high polish.

Although not absolutely essential to the present invention, it may be desirable at times to omit the usual rotatable bending roll 9 and to substitute therefor a stationary member such as is illustrated in Fig. 4 and designated 17. This member is also in the form of a hollow, substantially rectangular casing but is provided at one of its corners with a laterally offset portion 18 over which the sheet is deflected from the vertical to the horizontal. This member is likewise adapted to have circulated therethrough a suitable temperature control medium and the entire member or just that portion in contact with the glass may be constructed of a non-corrosive material. As the sheet is deflected from the vertical to the horizontal, it will be dragged over the member 17 and this dragging action will effect the smoothing or flattening out of the sheet.

In Fig. 3 is illustrated one way in which the members 12 and 13 may be mounted. As shown, these members are provided at opposite ends with the hollow tubular extensions 19 and 20 respectively, the extension 19 at each end of member 12 being carried by a support 21 fixedly secured to a base member 22, while the extension 20 at each end of member 13 is carried by a support 23 slidably mounted upon said base member and normally urged toward the first member by a compression spring 24. The compression springs 24 at opposite ends of member 13 are provided to normally urge said member inwardly toward member 12, but are of such a nature that the members can be readily moved apart to permit the passage of clay or other foreign matter therebetween and in this manner prevent injury to the highly polished surfaces thereof. The inward movement of member 13 is limited, however, by the adjustment of nut 25 upon bolt 26 carried by the support 23 at each end of said member and passing outwardly through the respective fixed bracket 27. The tubular extensions 19 and 20 facilitate the introduction of the cooling medium into the members 12 and 13 and its subsequent discharge therefrom.

It is to be understood that the form of the

invention herewith shown and described is to be taken as the preferred embodiment of the same, and that various changes in the shape, size and arrangement of parts may be resorted to without departing from the spirit of the invention or the scope of the subjoined claim.

I claim:

In sheet glass apparatus, means for drawing a sheet upwardly from a bath of molten glass, stationary members engaging opposite surfaces of the sheet at the base or meniscus thereof and having a wiping or smoothing action thereon, and means for yieldably urging one of said members toward the other.

Signed at Toledo, in the county of Lucas and State of Ohio, this 5th day of March, 1930.

JOHN L. DRAKE.
